[57] CLAIM

The ornamental design for a gardening implement, as shown and described.

DESCRIPTION

FIG. 1 is a side elevational view of my new design for a gardening implement, with phantom lines indicating a handle which forms no part of the claimed design, the opposed side of which is a mirror image and therefore not shown;

FIG. 2 is a top plan view of the implement shown in FIG. 1; FIG. 3 is a bottom plan view of the implement shown in FIG. 2;

FIG. 4 is a cross-sectional view taken along lines 4—4 in FIG. 2;

FIG. 5 is a front elevational view of the implement shown in FIG. 1; and,

FIG. 6 is a rear elevational view of the implement shown in FIG. 1.
